UNITED STATES PATENT OFFICE.

EUGENE GILLMAN AND LEAH SIEGEL, OF SEATTLE, WASHINGTON.

DESIGN FOR A CHILD'S ROMPER.

56,231.

Specification for Design. Patented Aug. 31, 1920.

Application filed May 6, 1920. Serial No. 379,417. Term of patent 7 years.

To all whom it may concern:

Be it known that we, EUGENE GILLMAN, a citizen of Russia, and a resident of the city of Seattle, in the county of King and State of Washington, and LEAH SIEGEL, a citizen of the United States, and a resident of the city of Seattle, in the county of King and State of Washington, have invented a new, original, and ornamental Design for Children's Rompers, of which the following is a

specification, reference being had to the accompanying drawing forming part thereof.

Figures 1 and 2 are, respectively, front and back views of the rompers, showing our new design.

We claim:

The ornamental design for a child's romper, as shown.

EUGENE GILLMAN.

LEAH SIEGEL.
